William A. McArthur

By Whitemore, Hubert, Whitemore, & Belknap

Attorneys

UNITED STATES PATENT OFFICE.

WILLIAM A. McARTHUR, OF DETROIT, MICHIGAN.

MUTE FOR WIND INSTRUMENTS.

Application filed July 3, 1922. Serial No. 572,741.

To all whom it may concern:

Be it known that I, WILLIAM A. McARTHUR, a citizen of the United States of America, residing at Ferndale, Detroit, in the county of Wayne and State of Michigan, have invented certain new and useful Improvements in Mutes for Wind Instruments, of which the following is a specification, reference being had therein to the accompanying drawings.

This invention relates to mutes for wind instruments and particularly for cornets and the like.

It is an object of the invention to provide an attachment for cornets and similar instruments which will so modulate the tone as to secure a close simulation of a French horn.

A further object is to form such an attachment with spring arms that may be snapped into engagement with the bell of a horn to accomplish a secure yet quick detachable mounting of the device on the horn.

Another object is to provide a mute attachment for horns which when not in use may be telescoped over the bell of the horn.

In the drawings:—

Figure 1 is a perspective view of the attachment;

Figure 2 is a sectional view of the same engaged with the bell of a horn.

In these views the reference character A designates a sleeve formed preferably of rolled sheet fiber, one end of said sleeve being closed by a disk of the same material, as indicated at B, and a plurality of arch shaped openings C being extended from the other end, arms D being formed between said openings. Said arms constitute supports for the device, their free ends being transversely channeled, as indicated at E, for engagement with the bell of a cornet or other horn F. The material comprising the sleeve A is sufficiently resilient that through proper proportioning of said sleeve, said arms may be adapted to engage the bell of the horn under tension, so as to hold the attachment quite securely in its position of use. Preferably each of the arms D is reinforced by a slight longitudinal bead F. Preferably mounting of the end plate B is accomplished by forcing the same into an annular bead G provided in the member A. It has been found desirable to reinforce each of the spring arms D terminally by a metal plate H exteriorly applied and conforming

to the curvature of said arm, said plates being held in place by rivets I. The space J formed within the sleeve A between its closed end and the openings C functions as a sound chamber and is highly important in obtaining the desired tone effect. The specified material (sheet fiber) employed to form the device is also a factor in obtaining the desired tone. By dash lines in Figure 2 is indicated the stored position of the device with respect to the bell of the horn F, the latter being telescopically embraced by the sleeve A in said position.

It is a feature of the construction that the spring arms D adapt the device to be mounted quite firmly upon the bell of the horn maintaining engagement therewith whether or not the horn is in position of use or any other position. The described mounting, however, is of a quick detachable nature since a slight manual effort will disengage the spring arms from the horn.

The tone resulting from the use of the described attachment is very smooth and clear and not distinguishable from the tone ordinarily produced only by a French horn.

It is to be noted that the arms D, are sprung slightly toward the axis of the attachment so that the bell of the horn terminally embraced by said arms may have a lesser diameter than that of the sleeve A. Thus clearance for the bell of the horn within said sleeve in stored position of the latter is assured.

What I claim as my invention is:—

1. A mute attachment for horns comprising a sleeve of fibrous material substantially closed at one end and formed at its other with resilient arms proportioned for snap engagement with the flared end of a horn.

2. A mute attachment for horns comprising a sleeve having a larger diameter than the bell of a horn and being substantially closed at one end, said sleeve being formed at its other end with openings for the egress of sound vibrations, between integral resilient arms detachably embracing the bell of said horn.

3. A mute attachment for a horn including a sleeve closed at one end, and means projecting forwardly from the open end of said sleeve for detachably securing the same to said horn, said sleeve having a greater diameter than the bell of said horn whereby said sleeve may receive the bell of said horn.

4. A mute attachment for a horn com-

prising a sleeve provided at one end with a lateral opening and integral resilient supporting arms, the other end of said sleeve being substantially closed, and metal plates reinforcing said arms.

5. A mute attachment for a horn comprising a sleeve provided at one end with a lateral opening, and arms detachably embrac-

ing the bell of said horn, the other end of said sleeve being closed, the diameter of the sleeve being slightly greater than that of the bell of said horn whereby said sleeve may telescopically embrace said bell.

10 In testimony whereof I affix my signature.

WILLIAM A. McARTHUR.
